United States Patent Office

Des. 211,287
Patented June 4, 1968

211,287

PAPER TOWELING

Philip Masnick, New York, N.Y., assignor to The Procter & Gamble Company, Cincinnati, Ohio, a corporation of Ohio

Filed Feb. 3, 1967, Ser. No. 5,675

Term of patent 14 years

(Cl. D59—2)

The figure is a plan view of a full width of paper toweling, the center portion shown broken away for convenience of illustration being unornamented.

I claim:

The ornamental design for paper toweling, as shown and described.
